UNITED STATES PATENT OFFICE.

OSWALD MACFARLANE, OF FORT WILLIAM, CANADA, ASSIGNOR OF ONE-HALF TO ANDREW ARTHUR, OF FORT WILLIAM, ONTARIO, CANADA.

HAND-TRUCK.

SPECIFICATION forming part of Letters Patent No. 793,794, dated July 4, 1905.

Application filed August 15, 1904. Serial No. 220,748.

To all whom it may concern:

Be it known that I, OSWALD MACFARLANE, of Fort William, Province of Ontario, Dominion of Canada, have invented certain new and useful Improvements in Hand-Trucks; and I do hereby declare that the following is a full, clear, and exact description of the same.

My invention relates particularly to railway or warehouse trucks; and it has for its object to provide trucks of this type with means for preventing the accumulation of dirt on its wheels.

The invention may be said, briefly, to consist of a scraper adjustably mounted upon the frame of the truck and adapted to be caused to bear upon the perimeter of the wheels and present a scraping edge thereto, such scraper being of particular construction.

For full comprehension, however, of my invention reference must be had to the accompanying drawings, forming a part of this specification, in which similar reference characters indicate the same parts, and wherein—

Figure 1 is a plan view of the under side of a truck provided with my invention. Fig. 2 is a longitudinal vertical sectional view taken on line A A, Fig. 1; and Fig. 3 is a transverse vertical sectional view taken on line B B, Fig. 1. Fig. 4 is perspective view of the scraping portion.

The truck-frame *b*, wheels *c*, axle *d*, and feet *e* are of usual construction.

My improved scraper consists of a tongue *f*, having a downwardly-inclined cross-piece *g* at one end, such cross-piece having its outer edge sharpened to a knife-edge, as at *h*, while a pair of bracing-strips *i* extend rearwardly from the opposite ends of this cross-piece and parallel to the tongue *f*. The tongue is slotted longitudinally, as at *k*, in position to coincide with the rearmost cross-bar *l* of the truck-frame, and a bolt *n*, having a square neck *n'*, is inserted downwardly through the tongue and through a U-shaped strap *o* upon the under side of the said cross-piece and has a butterfly-nut *o'* threaded thereon, while the tongue

is guided in such U-shaped strap and similar straps upon the under side of the cross-bars *l*. These straps are secured in place by bolts *o*, and they retain the scraper against lateral displacement and allow it freedom to move longitudinally, the bolt and butterfly-nut being adapted to lock the same in any position to which it may be adjusted.

A pair of brackets *p* are carried by the truck-frame adjacent to the wheels and in position to be borne upon by the bracing-strips *i* on the ends of the cross-piece of the scraper and maintain the knife-edge of the latter in bearing relation with the wheels. The lower end of the tongue and the cross-piece thereon bear upon the under side of the end cross-bar, thereby steadyng the scraper.

What I claim is as follows:

1. The combination with a truck, of a scraper consisting of a tongue extending longitudinally to the truck; a cross-piece formed rigidly upon one end of the tongue and having one edge sharpened and adapted to bear upon the perimeter of the truck-wheels; and means adjustably securing such scraper to the truck, substantially as described and for the purpose set forth.

2. The combination with a truck, of a scraper consisting of a tongue extending longitudinally to the truck; a cross-piece formed rigidly upon one end of the tongue and having one edge sharpened and adapted to bear upon the perimeter of the truck-wheels; means adjustably securing the scraper to the truck; and means for bracing the scraper, substantially as described and for the purpose set forth.

3. The combination with a truck having a series of cross-pieces extending parallel to the axis of its wheels, of a scraper consisting of a tongue *f* having a downwardly-inclined cross-piece *g* at one end, such cross-piece having its outer edge sharpened, a pair of bracing-strips *i* extending from the opposite ends of this cross-piece and parallel to the tongue, such tongue being slotted in position to coincide with one of the cross-bars of the truck-frame,

a bolt projecting through the cross-bar and slotted tongue and having a nut threaded thereon, and bearing-brackets *p* carried by the truck-frame adjacent to the wheels and 5 adapted to be borne upon by the bracing-strips, substantially as described and for the purpose set forth.

In testimony whereof I have affixed my signature in presence of two witnesses.

OSWALD MACFARLANE.
